BASE FOR RAYON PUMPS AND THE LIKE

Joseph Paul Laird, Philadelphia, Pa., assignor to
The Wicaco Machine Corporation, Philadelphia, Pa., a corporation of Pennsylvania

Application May 15, 1945, Serial No. 593,934

5 Claims. (Cl. 103—218)

1

My invention relates to new and useful improvements in bases for rayon pumps and has for an object to provide a base that will increase the efficiency of the rayon pump.

It is well known to those skilled in the art that rayon pumps are made with great accuracy and necessarily so as the acetate, viscose or cuprammonium etc., must be carefully meterized, also there must be an absence of pulsation or the denier of the thread will be affected. However, if the cast iron bases of the pumps (which are separate entities) are clamped to the main supply lines happen to have even small blow holes extending therethrough, the efficiency of the metering of the pumps will be adversely affected.

Furthermore, the viscose and acetate in travelling through these cast iron bases to the pump, have a tendency to rust the base and the accumulated rust will affect the quality of the rayon.

One of the objects of the present invention, therefore, is to provide a cast iron base for the rayon pump in which are inserted preferably stainless steel plugs or inserts through which the fluids will pass to thus both overcome the possibility of any accumulating rust in the passageways of the base and to furthermore provide against any blow holes that might otherwise extend from the passageways of the base to the upper surface and thus affect the meterizing of the pumps.

Still another object of the invention is to utilize a relatively cheap cast iron base and wherever there is a passageway in the base, to provide a stainless steel core or plug or insert, so that the viscose or acetate never comes in contact with the cast iron of the base, contacting only the walls of this stainless steel insert or inserts.

With these and other objects in view, the invention consists in certain and novel arrangements and combination of parts that will be hereinafter more fully described and pointed out in the claims.

Referring now to the drawings showing a preferred form of base and two modified forms:

Fig. 1 is a view in elevation of my improved base, parts of the uprights being shown in section;

Fig. 2 is a sectional view taken on line 2—2 of Fig. 1;

Fig. 3 is a fragmentary top plan view of one of the uprights;

Fig. 4 is a view partly in elevation and partly in section of a modified form of base showing a cutoff valve; and

Fig. 5 is a sectional view of a still further modi-

2

fied form of base in which the cutoff valve has been dispensed with.

Referring now for the moment to Fig. 1, there is shown the main supply pipe 1 for the acetate, viscose or other material from which the rayon is to be made. Clamped to this supply pipe 1 may be seen the base 2 which in this instance includes the two legs, the inlet leg 3 and the outlet leg 4, the body portion 5 which is semicircular on its bottom as at 6 to snugly rest on and hug the inlet pipe 1.

As also may be seen in Figs. 1 and 2, bosses 6 are provided on the opposite ends of the body portion in which the bolts 7 are threaded so that the clamp bars 8 may be pulled up tightly against the supply pipe to provide a tight fit and anchor said base in position.

Glancing now at Fig. 2 and at the inlet upright 3, it will be seen that the same is provided with a bore 9 extending through its entire length and in this bore is driven under great pressure, a stainless steel plug or insert 10. After this insert has been inserted as a permanent structure under great pressure, a passageway is drilled near its lower end as at 11 and a small locating tube 12 may be fitted therein so that this locating tube 12 will extend through an opening formed in the main supply pipe 1. Also drilled into the insert 10 from the top of the same is the angularly extending passageway 13, the lower end of this passageway and the upper end of the passageway 11 being offset as may be seen in Fig. 2 so that the flow of liquid may be regulated by the valve stem 14 which registers with the lower end of the passageway 13 and the upper end of the passageway 11.

The valve stem 14 is supported in the boss 15 and the valve gland nut 16. At the inner end of the gland nut is the washer 17 that may be of buna rubber or asbestos and in front of this will be the small stainless steel washer or insert 18. The threaded valve stem 14 will also be of stainless steel so that as the acetate or viscose passes up from the supply pipe 1 through the passageways 11 and 13 and out of the outlet 19 connected with the passageway 13, it has not come in contact with any of the cast iron metal of the base. On the other hand, it has come in contact with only the passageways formed in the stainless steel, thus avoiding any possibility of contaminating the acetate with any foreign substance such as rust which heretofore has been the case when the liquid simply passed through the cast iron base.

At the top of the upper passageway 13 there is

also inserted the stainless steel pipe plug 20. Also it will be seen that even the valve stem that is in the path of the acetate is of stainless steel so there is no possibility whatever of any rust getting into the acetate.

Furthermore, it will be seen that regardless of whether the base should have blow holes therein, by forming these passageways in the stainless steel, there will be no loss of pressure and the metering of the pump will not be adversely affected.

Still glancing at the upright 3, Fig. 1, there will be seen the stationary nipple 21 which is fitted within the cast iron upright and sealed in the stainless steel insert 10. In the outer end of this nipple will be partially supported the rayon pump (not shown) in the usual manner.

Thus, from the time the liquid passes from the base into the pump it has travelled through passageways formed of stainless steel.

Reference is now made to the opposite or outlet leg 4, wherein the same arrangement is carried out in that the passageways here are all formed in stainless steel plugs or inserts. Here the upper portion of the leg 4 is drilled or cast with the bore 25 in which is fitted under heavy pressure the stainless steel insert 26.

At right angles to the insert 26 may be seen the threaded adjustable nipple 27 which is likewise formed of stainless steel and is held in place by the lock nut 28 in which is secured a washer 29. To the rear of the nipple may also be seen the stainless steel plug 27' which extends well into the stainless steel insert 26.

Registering with the nipple is the outlet in the upper gland nut 30 that is also threaded into the stainless steel insert 26 while beneath the nut will be the washers 31. Thus, when the acetate goes through the stainless steel nipple 27 from the pump (not shown) it will pass up through the gland nut 30 to the supply (not shown) for the spinnerettes.

Thus, it will be seen that from the time the acetate leaves the mass supply pipe 1, until it passes out of the gland nut 30, that is, as far as the base is concerned, it has never come in contact with any of the cast iron of the base but only in contact with the passageway walls in the stainless steel inserts and with the stainless steel valves and nipples and glands as just described.

To repeat, even if the cast iron base should have blow holes therein, they could not in any way affect the metering of the pump and furthermore, there is no possibility of any rust accumulating and passing into the acetate to affect the quality of the rayon.

It will also be noticed that the stainless steel inserts are so arranged that the drilling or reaming of the base for these inserts may be done without presenting any machine setting-up difficulties.

Referring now to the modified form shown in Fig. 4, here again the stainless steel inserts are provided throughout the line of travel of the viscose or acetate.

It will be understood that I have only shown enough of the base to illustrate the invention. There is shown the body 50 with one leg 51 and the opposite leg 52. The leg 51 is drilled and reamed to receive the steel alloy insert 53 and this insert in turn is fitted with a central passageway 54 in which there is a stainless steel valve 55 with its handle 56, there being the outlet 57 registering with the fixed nipple 58.

As will be readily appreciated if the handle 75

58 is turned it will either turn on or off the supply of viscose depending on whether the port 59 opens or closes the outlet 57.

5 In the opposite leg 52 there will also be seen the stainless steel insert 60 with the stainless steel nipple 61 and the rear plug 61' and lock nut 62 with the upper gland nut 63; the passageway through the nipple, of course, registering with the passageway 64 registering with the gland nut 63.

The modification shown in Fig. 5 also shows a cast iron base having the body 75, the upright 76 and the upright 77, the upright 76 having the stainless steel plug 76' tightly and permanently fitted therein which plug is then drilled as at 78 and sealed by the plug 79, there being a passageway 80 connected therewith and leading to the fixed nipple 81.

20 The other upright 77 has the plug 82 therein and this plug is drilled to receive the outlet pipe 83 which passes through the gland nut 84, a washer 85 being on the inner end of the nut. Likewise, there is the nipple 86 that is drilled as at 87 and then recessed about its periphery at 25 88 and provided with a cross hole 89 so that the liquid may pass up into the outlet 83. Lock nuts 90 are shown for holding the nipple in place. Thus, it will be seen that in this form of base, too, the acetate never comes in contact with the cast iron of the base but only with the metal or rustless inserts.

30 From the foregoing it will be seen that I have provided a base or bases for rayon pumps, or pumps of a similar nature, wherein cast iron may be used to support the pump and by inserting steel plugs or inserts as illustrated above and certain stainless steel parts, all the advantages of a solid stainless steel base is obtained without the expense.

40 Furthermore, it is a relatively simple matter to install these inserts in bases already made as well as ones to be later made.

45 Finally, although I have mentioned stainless steel throughout the application as the material out of which the inserts, nipples and valves should be constructed, it will be understood that other stainless metals such as stainless bronze, and aluminum or even plastics that are almost metallic in their hardness might be used in place of the stainless steel, as the main object, of course, is to provide inserts that are stainless or rustless in their nature.

50 Many slight changes may be made without in any way departing from the spirit or scope of the invention.

Having thus described my invention what I claim is new and desire to obtain by Letters Patent is:

55 1. In a cast iron metal base for rayon pumps and the like, two connected uprights, relatively thick stainless inserts in the form of drive fit plugs in each of said uprights, stainless nozzles seated in the stainless inserts, one upright having a passageway formed in the stainless insert 60 registering with one of said nozzles and the other of said uprights having a passageway in said stainless insert registering with the other of said nozzles whereby fluid flowing through said inserts and nozzles contacts with only stainless walls.

65 2. In a cast metal base for rayon pumps and the like, a body portion and oppositely disposed uprights, one of the uprights having a central core 70 passing completely therethrough and the other of said uprights having a bore extending partly

therethrough, non-rustable relatively thick inserts in the form of drive fit plugs permanently secured in the said respective bores, non-rustable nipples extending towards each other from said uprights, and the said non-rustable nipples also respectively seated in the said non-rustable inserts, and the said non-rustable inserts provided with passageways respectively registering with said nipples whereby fluid passing through said passageways and nipples will contact only with the non-rustable inserts and nipples.

3. In a cast iron metal base for rayon pumps and the like, a body portion and oppositely disposed uprights, one of the uprights having the central bore passing completely therethrough and the other of said uprights having a bore extending partly therethrough, relatively thick stainless metal inserts in the form of drive fit plugs permanently secured in the respective bores, stainless metal nozzles extending towards each other from said uprights and respectively seated in the stainless metal inserts, the stainless metal insert of the one leg having a passageway registering with the nipple seated therein and the stainless metal insert in the other of said uprights likewise having an outlet passageway registering with its nipple whereby fluid flowing through said passageways and nipples will only contact with the stainless metal walls of the passageways and nozzles.

4. In a cast iron metal base for rayon pumps and the like, a body portion adapted to be clamped on a supply pipe, two oppositely disposed uprights integral with the body portion, one of the uprights having a bore extending completely therethrough and a relatively thick stainless steel insert in the form of a drive fit plug permanently secured therein, the said steel insert having a

- passageway adapted to communicate with the main supply pipe, a stainless steel nipple inserted in the insert and registering with the passageway, the other of said uprights having a bore passing partially therethrough and a relatively thick steel insert also in the form of a drive fit plug permanently mounted in said last mentioned bore, a stainless steel nipple seated in said insert and said stainless steel insert also having a passageway registering with said nipple whereby fluid flowing through said passageways and nipples will contact only with the stainless steel walls of the inserts and nipples.
5. In a cast iron metal base for rayon pumps and the like, a body portion adapted to be securely clamped on a supply pipe, two oppositely disposed uprights integral with the body portion, one of the uprights having a bore extending completely therethrough and a relatively thick stainless steel insert in the form of a drive fit plug permanently secured within said bore, the said steel insert having a passageway adapted to communicate with the main supply line, a stainless steel valve extending into said passageway, a stainless steel nipple seated in the insert and registering with the passageway, the other of said uprights having a bore passing partially therethrough and a relatively thick steel insert also in the form of a drive fit plug permanently mounted in said last mentioned bore, a stainless steel nipple also seated in said last mentioned insert and said stainless steel insert also having a passageway registering with said last mentioned nipple whereby fluid flowing through said passageways and nipples will contact only with the stainless steel walls of the insert valve, insert passageways, and nipples.

JOSEPH PAUL LAIRD.
